UNITED STATES PATENT OFFICE

2,004,402

ATOMIZER

John Edward Conklin, Brooklyn, N. Y.

Application April 7, 1934, Serial No. 719,523

3 Claims. (Cl. 128—173)

This invention relates to improvements in atomizers of the type employed for treating throat and nasal passages with medicated liquid in finely atomized or spray form.

One of the objects of my invention is the provision in an atomizer of the type under consideration of a nasal tip or guard which is capable of a quick mounting on the discharge nozzle of the atomizer and of removal therefrom while at the same time the said tip is always connected to the instrument and can not be either lost or mislaid.

Another object of my invention is to provide an instrument of the type specified with a nose guard or tip that may have a permanent connection with a carrier member slidable along the discharge tubes and permanently interlocked with said tubes and the nozzle.

Still another object of my invention is to provide a guard or nasal tip construction formed in two hinged parts in combination with discharge tubes having forward end portions of reduced width and portions adjacent to their outer ends sprung apart to provide an outwardly-sprung or bulged portion merging with an inclined or tapering portion and terminating in transversely-turned terminal ends which are inserted in a nozzle, whereby the slidable carrier member may be moved to opposite sides of said outwardly sprung or bulged portion and the forward end of reduced width will permit mounting and demounting of the tip body on the sliding member and the assembled parts may be moved rearwardly over the sprung or bulged portion to provide a firm mounting for such assembled parts, and after use may be by a forward motion on the reduced terminal ends be demounted from its operative to inoperative position and then moved rearwardly along the tubes to any suitable position along the rear part of said tubes.

Still another object of my invention is, in a construction of the type specified, to provide a sliding ferrule member having means for hingedly connecting a tip or guard body thereto and an open forward end adapted to receive and form a close connection with the rear end of said body and also having stop means for engaging the outer terminal end to prevent removal of the device from the tubes.

Still another object of my invention is to provide in combination with a sliding member of the type specified a tube-reinforcing tie element provided with grooves through which the stops are adapted to slide in its movement on the tubes.

With these and other objects in view, the invention comprises the combination of members and

arrangements of parts so combined as to co-act and co-operate with each other in the performance of the functions and the accomplishment of the results herein contemplated, and comprises in one of its adaptations the species or preferred form illustrated in the accompanying drawing in which:—

Figs. 1 and 2 are top and plan views of an atomizer embodying my invention with the removable but permanently attached nose guard 10 mounted thereon.

Fig. 3 is a view in side elevation of the atomizer shown in Fig. 2 with the nose guard demounted from the nozzle and moved backwardly along the tubes.

Fig. 4 is an enlarged plan view of the atomizer discharge-tubes and nozzle showing the nose-guard or nasal tip in section and moved to the forward end of the instrument for demounting or mounting the body portion on the slide member. 20

Fig. 5 shows guard or nasal tip moved back into operative position over the nozzle;

Fig. 6 is a section on the line 6—6 of Fig. 5 and

Fig. 7 is a view in plan of the open end of the nasal tip body disassembled from the tubes and 25 from the slidable ferrule member.

Referring now to the drawing which illustrates a preferred embodiment of my invention, 1 indicates a pair of air-and-liquid discharge tubes of an atomizer, which extend in parallel relationship to each other from an atomizer-head 2, on a bottle 3, air being supplied to the head 2 through tubes 4 and 5 from a bulb or other source of supply not shown. The parallel discharge tubes 1 are preferably tied together intermediate their ends in closely-spaced relationship and, as shown, I provide for this purpose a tie member 6. Said tubes 1 have portions adjacent to their outer ends sprung apart to provide an outwardly bulged portion 1' and an inwardly converging portion 1^a of reduced width and said tubes terminate in transversely-turned portions 1^b which form trunnions and fit into transversely-disposed aligned bores provided in a nozzle 7 adjacent to the rear end thereof, as indicated in Figs. 4 and 5, it being understood that the transverse bores of the two discharge tubes open into a common longitudinal discharge bore 7' in the said nozzle 7. The outer sides of the converging portion 1^a of the discharge tubes 1 taper outwardly from the bulged portion 1' for a short distance and portion 1^a and 1' of said tubes preferably have resilience to permit

the mounting thereon and frictional engagement therewith of a nasal tip 8, the construction, 55

mounting and attachment of which to the tubes forms an important part of my invention.

In the atomizing devices of the type under consideration heretofore manufactured, loose nasal tips substantially barrel-shaped in configuration are mounted on the ends of the discharge tubes, and it frequently happens that a loose tip is lost or mislaid when the same is removed to permit facile use of the atomizer within the mouth for treatment of the throat, and it is an object of this invention to provide an atomizer with a nasal tip which will have a permanent connection with the tubes and can not therefore, be either lost or mislaid and which furthermore will be capable of quick mounting on the nozzle to permit operation of the instrument for spraying the nose and quick demounting and sliding backward on the tubes of said nasal tip to permit more facile operation of the instrument within the mouth for treatment of the throat of the user.

With these ends in view, I provide a nasal tip 8 comprising a substantially barrel-shaped body or tip member 8' having a hinge connection with a slidable carrier-member 8^a having a permanent interlocking and sliding connection with the tubes. As illustrated, the slidable carrier member 8^a comprises a cylindrical ferrule open at its forward end and partially closed by the wall 8^b at its rear end, which wall 8^b is provided with a mounting opening 8^b' through which the tubes are adapted to pass to permit the mounting of the slidable carrier member or ferrule 8^a thereon. The opposite edges of this opening 8^b' are, as shown, provided with inwardly-disposed stop portions 8^c which extend toward each other between the parallel tubes 1 and when the sliding carrier is moved outwardly to the forward end of the tubes will abut against the rear end of the nozzle and provide stops which prevent the slide from moving over the nozzle and being disconnected.

In the preferred embodiment of my invention, these stops 8^c are spaced apart and that portion of the tie member 6 intermediate the tubes is channelled upon opposite sides to permit the stops 8^c to pass through these channels and thus to allow the sliding movement of the slidable carrier member 8^a rearwardly beyond said tie-member 6.

As illustrated in Figs. 3, 5, and 7, the carrier member 8^a is provided with an inwardly-turned hinge-strap 9 which passes through an opening 10 in the body or tip member 8^a of the nasal tip, to form a loose hinged connection between the open forward edge of the sliding carrier member 8^a and the rear end of the body or tip member 8', which rear end of the body member is also open and is adapted to snugly fit into the open forward end of the carrier member 8^a. These two members 8^a and 8' preferably are interlocked with each other in assembled position and as shown a portion of the rear edge of the body member is provided with a bulge 11 which when swung or moved into assembled position with the slidable carrier-member will cause the two parts to have a releasable fastening engagement.

In operation, the nasal tip being in the position at the rear end of the tube as shown in Fig. 3, is slid forwardly over the tie member 6 and to the position at the forward end of the tube-bulge 1' and tapering portion 1^a of the tubes, and thereupon the body member 8' is swung upwardly to cause latching bulge 11 to engage and interlock

with the forward end or lip of the carrier member 8^a. The two-part nasal tip now extends forwardly beyond the nozzle and is then moved rearwardly, and in such movement frictionally engages the tapering portions 1^a and bulge portion 1' of the tubes. The rearward movement of the tip is limited by the engagement of the outer end of the nozzle 7 with the edges of the aperture 8^d in the forward end of the nasal tip. Obviously, when the nasal tip is in the position shown in Figs. 1, 10 2 and 5, this nasal tip may be used as a guard and centering element for the nozzle in treatment of the nose, and when it is desired to use the instrument for treatment of the throat through the mouth, the entire tip is first moved 15 forwardly, the body member is pressed downwardly to unfasten the latching bulge 11 from the carrier lip and the said carrier member 8' with the body portion, in the position shown in Fig. 3, is then moved rearwardly to the opposite 20 end as shown in said Fig. 3. When the nasal tip is in the position shown in Fig. 3 it is out of the way for treatment of the throat by the instrument, but it cannot be lost or mislaid because it has a permanent connection with the tubes 1. 25

Having described my invention, I claim:—

1. In an atomizer, a nozzle, a pair of air and liquid discharge tubes carrying said nozzle and extending rearwardly therefrom in spaced relationship to a source of liquid and air supply, and a two-part nasal tip mounted on said tubes and comprising a body member adapted to fit over the nozzle and a slidable carrier member movable along said tubes and having a hinge-connection with said body member and a permanent slidable connection with said tubes.

2. In an atomizer, a nozzle, a pair of air and

liquid discharge tubes carrying said nozzle and

extending rearwardly therefrom in spaced rela-

tionship to a source of liquid and air supply, and

a two-part nasal tip mounted on said tubes and

comprising a body member adapted to fit over the

nozzle and a slidable carrier member movable

along said tubes and having a hinge-connection

with said body member and a permanent slidable

connection with said tubes, said carrier member

comprising a ferrule having an open forward end

and said body member comprising a barrel-

shaped element having an open rear end releas-

ably connected to the open forward end of said

ferrule.

3. In an atomizer, a nozzle, a pair of air and

liquid discharge tubes carrying said nozzle and

extending rearwardly therefrom in spaced rela-

tionship to a source of liquid and air supply, and a

two-part nasal tip mounted on said tubes and

comprising a body member adapted to fit over the

nozzle and a slidable carrier member movable

along said tubes and having a hinge-connection

with said body member and a permanent slidable

connection with said tubes, said carrier member

comprising a ferrule having an open forward end

and said body member comprising a barrel-

shaped element having an open rear end releas-

ably connected to the open forward end of said

ferrule, said tubes having a bulge and tapering

portion adjacent to their forward ends and said

nasal tip being adapted to frictionally engage

said tapering and bulged portions.

CERTIFICATE OF CORRECTION.

Patent No. 2,004,402.

June 11, 1935.

JOHN EDWARD CONKLIN.

It is hereby certified that error appears in the printed specification of the above numbered patent requiring correction as follows: Page 2, second column, line 66, claim 3, for "bugle" read bulge; and that the said Letters Patent should be read with this correction therein that the same may conform to the record of the case in the Patent Office.

Signed and sealed this 6th day of August, A. D. 1935.
